UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

DESIGN FOR A LAMP-BURNER.

SPECIFICATION forming part of Design No. 27,530, dated August 17, 1897.

Application filed June 18, 1897. Serial No. 641,365. Term of patent 7 years.

To all whom it may concern:

Be it known that I, LEWIS J. ATWOOD, a citizen of the United States, residing at Waterbury, in the county of New Haven and State of Connecticut, have invented a new Design for a Lamp-Burner, of which the following is a specification.

The leading feature of this design for a lamp-burner consists in the design of the burner-base, with alternate plain and embossed bands in radial planes around inside the chimney-holder.

In the accompanying drawings, Figure 1 is a side view of the design for a lamp-burner, and Fig. 2 is a plan view.

The general configuration of the burner is circular, and within the chimney-holder A the burner-base rises, and the surface is ornamented with plain bands 2, alternating with roughened embossed bands 3, occupying 20 substantially radial planes around the base.

I claim—

The design for a lamp-burner, substantially as described and shown.

Signed by me this 14th day of June, 1897. 25

L. J. ATWOOD.
